UNITED STATES PATENT OFFICE.

ANNIE L. MEEKS, OF GADSDEN, ALABAMA.

DESIGN FOR A TIRE.

53,511.

Specification for Design.

Patented July 8, 1919.

Application filed February 19, 1917. Serial No. 149,686. Term of patent 3½ years.

To all whom it may concern:

Be it known that I, ANNIE L. MEEKS, a citizen of the United States, residing at Gadsden, in the county of Etowah and State of Alabama, have invented a new, original, and ornamental Design for a Tire, of which the following is a specification, reference being had to the accompanying drawings, forming part thereof.

Figure 1 is a fragmentary edge view, Fig. 2 is a fragmentary side elevation of a tire showing my improved design.

I claim:—

The ornamental design for a tire as shown.
ANNIE L. MEEKS.
